FOUNTAIN COMB

Clifford M. Raemer, Terre Haute, Ind.

Application April 29, 1933, Serial No. 668,597

19 Claims. (Cl. 132—13)

This invention relates to a fountain comb structure.

The chief object of this invention is to provide a fountain comb structure suitable for applying a rather heavy or viscous liquid to the hair and with a structure that is a unitary arrangement and wherein the flow of liquid therefrom may be readily controlled and furthermore will not clog, and which comb structure may be readily held, 10 operated and controlled with one hand.

The chief feature of the invention consists in providing a comb structure of the character set forth, wherein the liquid is discharged from the reservoir or supply chamber to the teeth of the 15 comb by a film or sheet type discharge.

Another feature of the invention consists in the formation of the reservoir such that it detachably receives the comb, so that the comb may be readily removed for cleaning or replacement, 20 and the further formation of the combined structure such that the valve mechanism is normally constrained toward closed or shut-off position and may be readily manipulated into the adjusted open position through the use of the thumb, the 25 barrel or main portion of the reservoir being adapted for encircling by the hand and the barrel or reservoir being exteriorly provided with a finger gripping surface.

Another feature of the invention consists in 30 the formation of the comb structure such that it is readily adapted for mounting upon a simple convenient stand when not in use.

The full nature of the invention will be understood from the accompanying drawing and the 35 following description and claims:—

In the drawing, Fig. 1 is a side elevation of the fountain comb structure embodying the invention and the support associated therewith, the device being substantially in full size.

40 Fig. 2 is a transverse sectional view taken on line 2—2 of Fig. 1, and in the direction of the arrows.

Fig. 3 is a similar view taken on line 2—2 of Fig. 1 and in the direction of the arrows.

45 Fig. 4 is a similar view taken on line 4—4 of Fig. 1, and in the direction of the arrows.

Fig. 5 is a bottom plan view of the comb receiving portion and the discharge outlet of the throat, and a sectional view of the comb and may be considered as taken in the plane of line 5—5 of Fig. 1, and in the direction of the arrows.

Fig. 6 is a top plan view of the support with the fountain comb removed, parts being broken away to condense the figure.

55 Fountain comb structures have heretofore been

of the character wherein the liquid to be applied by the comb teeth is supplied through a plurality of ports or apertures which communicate with a common chamber and said ports and apertures discharge at the root, or roots, of the teeth of the comb portion, or said ports extend through the comb and turn laterally near the end of the teeth, the teeth being hollow for said purpose, or extend to the end of the teeth, in the latter instance, the teeth being entirely hollow as set forth. In all of these constructions the use of a viscous liquid of a viscosity approaching that of heavy glycerine, or the like, is practically impossible due to clogging, chiefly due to capillary attraction between the liquid and the walls of the ports adjacent the discharge.

The present invention seeks to overcome this difficulty by providing that the liquid supplied to the comb and distributed to the hair by means of the comb, is supplied to said comb as a sheet or film that is substantially coextensive with the length of the comb, and in the present embodiment of the invention is supplied to but one face of the comb, because one side wall of the throat serves as a comb support and it is the side against which the comb bears as it is passed through the hair.

It will be readily apparent that when ports are formed in the comb, it is practically impossible to clean such a comb, that is clean it externally, with any facility between applications to different heads, and it is practically impossible to clean the comb when it becomes clogged. The present invention eliminates any possibility of any clogging and permits the ready removal of the distributing comb for rapid cleaning between the successive operations upon different heads, as well as permits comb replacement when one or more teeth thereof are broken.

In Figs. 1 and 6 there is illustrated a conventional support for the fountain comb structure, and in said figures 10 indicates a base and 11 two upstanding supports or uprights which terminate in arcuate grooves 12 upon which a cylindrical barrel 13 having the closed end 14 constituting the reservoir or magazine is supported. The opposite end of the tubular magazine is open and is externally threaded. A cap 16 is internally threaded and closes the magazine. The cap has a port 18 that is arranged for positioning substantially opposite the reservoir discharge opening, hereinafter described.

A tubular valve 19 is nested within the cylindrical magazine, and projecting laterally therefrom is a finger piece 20, in the present form of

110

the invention the same being extended through the tubular valve member 19 and suitably secured to the inner surface thereof as at 21. This method of mounting is provided to insure rigidity and 5 firm connection between the finger piece and the valve member. The valve member 20 at its exposed portion includes a projection 22 that is adapted to serve as a spring seat or retainer for spring 23, the opposite end of which is telescopically associated with the well 24 of an arcuate housing 25. The end 26 of the arcuate housing 25, when the magazine is grasped in the right hand, seats approximately at the inside of the index finger at the second joint thereof.

10 15 The cylindrical casing adjacent the threaded end is provided with a longitudinal slot 27 and said slot includes a lateral extension 28 at its closed end. The longitudinal portion 27 of the slot is provided to permit the ready insertion and 20 removal of the tubular valve, and it is noted that the tubular valve herein is shown as of a length equal to the inside length of the cylindrical magazine. The arcuate portion 28 of the slot is provided to permit oscillatory movement of the cylindrical valve. The spring 23 normally retains the valve in closed position and when the magazine is grasped in the right hand, the thumb bears on the finger piece 20 and the valve may be turned in to the desired adjusted open position 25 30 in opposition to the spring 23.

Extending from a point adjacent the threaded portion of the magazine and for a considerable distance longitudinally along the magazine, is a throat structure 29. Arcuately offset from said 35 throat structure and substantially coextensive therewith, there is formed upon the exterior of the magazine or casing, an elongated parallel abutment 30. When the magazine is grasped in one hand, the middle and two fingers of the hand 40 have their tips positioned in the groove formed between the throat 29 and the abutment 30, see Figs. 3 and 4, other portions of said fingers bear upon the surface of the abutment 30 which is knurled, or otherwise fashioned to provide a frictional engagement. The peripheral exterior 45 of the cap is also knurled.

The throat 29 includes an elongated mouth or opening 31, and in the same is positioned an offset portion 32. This provides a longitudinal 50 extension 33—34 of the mouth opening, and an inner seat 36 adjacent the extended portion 33. The valve member includes a longitudinal slot 35 that is substantially of the same length as the throat opening 31.

55 A comb having the back 37 and the teeth 38 is seated in the throat, and the top edge of the comb bears on the portion 36 at each end of the throat, and the two sides of the back of the comb at the ends are frictionally nested in the 60 extensions 33—34 of the throat 31. This permits the comb to be readily detached from the throat structure for cleaning or replacement. It will be noted the width of the throat 31 is approximately double that of the thickness of the comb, 65 so that when the valve opening 35 partially or fully registers with the opening 31 in the magazine, a film of liquid from the magazine will discharge into the throat and pass down one side of the back of the comb and thence to the respective 70 teeth. There is no possibility of clogging or stoppage of the flow due to capillary attraction, since the single orifice is of sufficient magnitude to prevent such action. The operation is as follows:—

75 The comb is seated in the throat. The reservoir or magazine is filled with the liquid to be distributed by the comb. The cap is then screwed on the magazine with the port 18 positioned such that it is substantially diametrically opposite the throat opening 31. The device, until it is to be used, may be rested on the support structure as described. When the device is to be used, it is grasped in the right hand, as herein before indicated, the thumb on the finger piece or valve control member 20, the index finger bearing on the end 26 of the portion 25, and the three remaining fingers bearing on the casing between the throat 29 and the portion 30. Thus a perfect gripping arrangement is obtained. Pressure applied by the thumb on the exposed portion 20 rotates the valve member so that the elongated slots or ports in the valve member and throat register partially or completely, as desired, and when such registration occurs, the film of the liquid discharges by gravity on to one face of the back of the comb or the side of the comb and thence passes downwardly along the exterior of the teeth, and in the combing of the hair this liquid is transferred to the hair and removed from the teeth of the comb. The operation is continued until all the hair on the head operated upon is supplied with the liquid.

It will, of course, be readily apparent that instead of an interiorly arranged valve structure, an exteriorly arranged valve structure may be provided. However, the interiorly arranged valve structure offers certain advantages and prevents the leakage or escape of liquid, which is characteristic of the exteriorly arranged valve modification.

Said modification as well as others which will readily suggest themselves to those skilled in the art to which this invention applies, are all considered to be within the broad scope of this invention, reference being had to the appended claims.

The invention claimed is:—

1. In combination, a comb, a reservoir for a semi-viscous liquid supporting said comb, and means associated with the reservoir for discharging the liquid therefrom to the comb in substantially sheet or film form.
2. In combination, a comb, a reservoir for a semi-viscous liquid supporting said comb, means associated with the reservoir for discharging the liquid therefrom to the comb in substantially sheet or film form, said means constituting the sole supporting connection between the comb and reservoir to provide a unitary arrangement and direct the sheet discharge to the comb.
3. In combination, an elongated reservoir having an elongated throat with an elongated inlet slot providing the communication therebetween, valve means controlling the discharge from the slot, and a comb supported by the reservoir in juxtaposition to the slot for film or sheet discharge therefrom to the comb.
4. In combination, an elongated reservoir having an elongated throat with an elongated inlet slot providing the communication therebetween, valve means controlling the discharge from the slot, and a comb supported by the reservoir in juxtaposition to the slot for film or sheet discharge therefrom to the comb, said throat nestingly receiving and supporting said comb.
5. In combination, an elongated reservoir having an elongated throat with a single elongated inlet slot substantially coextensive with the throat and providing the communication therebetween, valve means controlling the discharge from the slot, and a comb supported by the reservoir in juxtaposition to the slot for film or sheet discharge therefrom to the comb.

- taposition to the slot for film or sheet discharge therefrom to the comb.
6. In combination, an elongated reservoir having an elongated throat with a single elongated inlet slot substantially coextensive with the throat and providing the communication therebetween, valve means controlling the discharge from the slot, and a comb supported by the reservoir in juxtaposition to the slot for film or sheet discharge therefrom to the comb, said throat nestingly receiving and supporting said comb. 80
7. A one hand supportable and operable magazine comb including in combination, a reservoir having a liquid discharging throat, a rotary valve therefor including an exposed thumb-engageable and operable portion, and means adjacent the throat and forming therewith a finger tip receiving groove. 85
8. A one hand supportable and operable magazine comb including in combination, a reservoir having a liquid discharging throat, a rotary valve therefor including an exposed thumb engageable and operable portion, means adjacent the throat and forming therewith a finger tip receiving groove, one end of the reservoir being open, and cap means for said open end for reservoir refilling. 90
9. In combination, an elongated reservoir having an elongated throat with an elongated inlet slot providing the communication therebetween, valve means controlling the discharge from the slot, and a comb supported by the reservoir in juxtaposition to the slot for film or sheet discharge therefrom to the comb, said throat having comb seating portions therein and said comb being detachably seated in the throat and between said portions. 100
10. In combination, an elongated reservoir having an elongated throat with a single elongated inlet slot substantially coextensive with the throat and providing the communication therebetween, valve means controlling the discharge from the slot, and a comb supported by the reservoir in juxtaposition to the slot for film or sheet discharge therefrom to the comb, said throat having comb seating portions therein and said comb being detachably seated in the throat and between said portions. 105
11. In a fountain comb, the combination of a cylindrical reservoir having an exteriorly positioned longitudinally extending throat with an elongated slot connection providing the communication therebetween for sheet discharge, an oscillatable arcuate valve member seated in the reservoir adjacent the slot connection for controlling liquid flow therethrough, and an exposed portion for moving said valve member. 110
12. In a fountain comb, the combination of a cylindrical reservoir having an exteriorly positioned longitudinally extending throat with an elongated slot connection providing the communication therebetween for sheet discharge, an oscillatable arcuate valve member seated in the reservoir adjacent the slot connection for controlling liquid flow therethrough and normally constrained toward cutoff position, and an exposed portion for moving said valve member into the desired open position. 115
13. In a fountain comb, the combination of a cylindrical reservoir having an exteriorly positioned longitudinally extending throat with an elongated slot connection providing the communication therebetween for sheet discharge, an oscillatable cylindrical valve member seated in the reservoir adjacent the slot connection and having an elongated slot arrangement therein for controlling liquid flow therethrough and normally constrained toward cutoff position, an exposed portion for moving said valve member into the desired open position, said exposed portion having a spring seat, an external socket upon said reservoir, and a spring having one end seated in said socket and the other end associated with the exposed portion and the other end associated with the exposed 120
14. In a fountain comb, the combination of a cylindrical reservoir having an exteriorly positioned longitudinally extending throat with an elongated slot connection providing the communication therebetween for sheet discharge, an oscillatable cylindrical valve member seated in the reservoir adjacent the slot connection and having an elongated slot arrangement therein for controlling liquid flow therethrough and normally constrained toward cutoff position, and an exposed portion for moving said valve member. 125
15. In a fountain comb, the combination of a cylindrical reservoir having an exteriorly positioned longitudinally extending throat with an elongated slot connection providing the communication therebetween for sheet discharge, an oscillatable arcuate valve member seated in the reservoir adjacent the slot connection for controlling liquid flow therethrough, an exposed portion for moving said valve member, said exposed portion having a spring seat, an external socket upon said reservoir, and a spring having one end seated in said socket and the other end associated with the exposed portion and the other end associated with the exposed 130
16. In a fountain comb, the combination of a cylindrical reservoir having an exteriorly positioned longitudinally extending throat with an elongated slot connection providing the communication therebetween for sheet discharge, an oscillatable arcuate valve member seated in the reservoir adjacent the slot connection for controlling liquid flow therethrough and normally constrained toward cutoff position, an exposed portion for moving said valve member into the desired open position, said exposed portion having a spring seat, an external socket upon said reservoir, and a spring having one end seated in said socket and the other end associated with the exposed portion and the other end associated with the exposed 135
17. In a fountain comb, the combination of a cylindrical reservoir having an exteriorly positioned longitudinally extending throat with an elongated slot connection providing the communication therebetween for sheet discharge, an oscillatable cylindrical valve member seated in the reservoir adjacent the slot connection and having an elongated slot arrangement therein for controlling liquid flow therethrough, an exposed portion for moving said valve member, said exposed portion having a spring seat, an external socket upon said reservoir, and a spring having one end seated in said socket and the other end associated with the exposed portion and the other end associated with the exposed 140
18. In a fountain comb, the combination of a cylindrical reservoir having an exteriorly positioned longitudinally extending throat with a slot connection providing the communication therebetween for sheet discharge, an oscillatable cylindrical valve member seated in the reservoir adjacent the slot connection and having an elongated slot arrangement therein for controlling liquid flow therethrough and normally constrained toward cutoff position, an exposed portion for moving said valve member into the desired open position, said exposed portion having a spring seat, an external socket upon said reservoir, and a spring having one end seated in said socket and the other end associated with the exposed portion and the other end associated with the exposed 145
- 79
- 75

portion spring seat and imposing said constraint upon the valve member.

19. In combination a casing having an elongated chamber therein, throat means rigid with 5 the casing and having an elongated opening therein, said means having noncapillary com-

munication with the chamber, valve means for controlling the discharge from the chamber to the throat, and a comb supported in juxtaposition to the chamber and being sheet fed from the throat.
